DEXTER D. HARDY, OF CINCINNATI, OHIO, ASSIGNOR TO HENRY J. BEHRENS, HENRY C. DART, AND EDWARD DART, OF NEW YORK, N. Y.

Letters Patent No. 77,373, dated April 28, 1868.

IMPROVEMENT IN ROTARY ENGINES.

The Schedule referred to in these Letters Patent and making part of the same.

TO WHOM IT MAY CONCERN:

Be it known that I, DEXTER D. HARDY, of Cincinnati, Hamilton county, Ohio, have invented a new and useful Improvement in Rotary Engines; and I do hereby declare that the following is a full, clear, and exact description thereof, reference being had to the accompanying drawings, making a part of this specification.

This is an improvement in the class of rotary engines, having a pair of pistons or winged heads, which, being connected by proper gearing, revolve together, within a suitable space, by the action of steam upon the wing or wings of each shaft alternately, so as to produce a continuous, uniform, and unintermittent motion.

Figure 1 is a section of an engine embodying my invention, taken in a plane parallel to that of rotation.

Figure 2 is a section at right angles to the above, taken at the line X X, fig. 1.

I employ a shell, case, or cylinder, of oval exterior, and of similar form interiorly to that described in a patent granted, on the 5th day of March, 1861, to myself and John J. Morris; that is to say, with sides A, having an interior composed of segments of equal cylinders, closed by heads B B', having axial perforations C for the shafts D D'.

Concentric with and surrounding each axial perforation within the case, is a hub, E E', whose side nearest to its fellow has a curved recess or concavity, F, concentric with, and of equal radius and curvature to, the exterior periphery of the opposing piston.

Each shaft has a disk or collar, G G', which works just outside the end of the hub, and carries a semi-annular wing or piston, H H', adapted to fit and revolve within the annular segmental spaces I I', between the hubs E E' and the shell A.

When nearly or quite semi-annular, the end, h, of each piston is concaved, so as to permit the free passage of the other, the curve of each piston being such as to correspond with the sweep of the connecting-point of the other.

The two shafts are connected by twin gears J J', so as to revolve together, and in concert, although the steam acts alternately on either piston, so that the, for the time being, effective piston, is thus made to drive the other, and *vice versa*.

The power may be taken off from either or both shafts by pulley K, or a crank, or gearing, either of the cog or frictional kind. The inner side of the head next to the disks G G' is recessed to receive them.

In the illustration, the steam entering the lower port is seen impelling the left-hand piston, and, in so doing, enlarging the space between the lower end of said piston and the periphery of the right-hand piston, the space between the upper end of the effective piston and the said periphery undergoing a corresponding contraction, and the spent steam escaping therefrom through the upper port.

The upper points or horns of the pistons having passed each other, the hitherto imprisoned steam on the right-hand side escapes, the left-hand piston still remaining effective until the said horns have again passed each other at the bottom of the case, when the right-hand piston begins to take steam, and to drive, in its turn, the now non-effective left-hand piston.

My present improvement has some advantages over the aforesaid joint invention of myself and Morris.

The rubbing-surfaces of the parts whose coaction is the effective medium of availing the force of the steam do not, as in said joint invention, touch by a mere line, so as to leak steam, but in every case present the extended bearing of corresponding convex and concave cylindrical arcs, and the concave recess of the hub is especially useful by affording an extended steam-joint, which, in the aforesaid invention, depended on the nice adaptation of the horns, which had to be of almost the full semicircular extent, or one hundred and eighty degrees, to avoid leaking; whereas in my present improvement the horns may be shortened, or even rounded off, and thus avoid any leaking of steam between the horns.

This device, although in the above description spoken of exclusively as a steam-engine, is equally applicable as a pump, or as a water-meter.

I have selected, to illustrate my invention, what I deemed its simplest form, but do not desire to restrict

myself thereto; as, for example, the piston may be duplicated on each head, and consist of two opposite quadrants. The hubs also may be of proportionally smaller, and with shallower recesses.

I claim herein as new, and of my invention—

1. The concentric fixed hubs, recessed substantially as described, in combination with the two geared shafts, their attached pistons, and the cylinder or case, substantially as set forth.

2. The pistons, attached to the facing sides of the two disks, secured to their respective shafts, and so arranged that the piston or pistons of one shaft work against the face of the disk of the other shaft, substantially as herein described.

In testimony of which invention I hereunto set my hand.

DEXTER D. HARDY.
